GARMENT LOOM

Clara C. Golden, New York, N. Y.

Application March 24, 1941, Serial No. 384,968

2 Claims. (Cl. 28—15)

The purpose of this invention is to provide a relatively small hand loom for weaving garments and particularly parts thereof which may readily be adjusted to any pattern or outline of any section or part of a garment so that the entire section or part may be woven as a unit, and which may also be set so that any device or object, other than a garment, may be woven thereon.

The invention is a loom comprising a plurality of strips of various lengths, having comb teeth at one or both edges, and means adjustably securing the strips together, and also suitable braces or supports for holding the strips assembled.

Looms have been made of various shapes and sizes and some have been provided with parts of different shapes and others adjustable, but in substantially all of these it is necessary to weave in squares or with slight variations, and these must be sewed or attached to form a garment, and this is objectionable when weaving garments because parts of garments are of odd shapes and it is difficult to weave these parts without cutting the material away.

The object of this invention is therefore, to make it possible to weave these parts of odd shapes directly to the shape desired.

Another object is to provide a loom that may readily be shaped to substantially any shape, size or design.

Another object is to provide a loom made up of small sections of various shapes so that the sections may be assembled to form an outline of a pattern or the like.

Another object is to provide a loom that may readily be changed from one pattern, size or design to another.

A further object is to provide a telescoping needle adapted to be used for weaving on a relatively wide loom.

And a still further object is to provide a loom that may readily be made up to any pattern, size or design which is of a simple and economical construction.

With these ends in view the invention embodies a frame formed of a plurality of relatively short pieces of various shapes, such as, curves, angles, clips and straight pieces, with projections forming teeth at one or both sides, holes therein, braces, and bolts or other fastening devices for holding the said pieces together.

Other features and advantages of the invention will appear from the following description taken in connection with the drawing, wherein:

Figure 1 is a plan view of a loom made up of

small sections and shaped to the contour of a sleeve of a garment.

Figure 2 shows a similar loom shaped to one of the panels of a coat or the like.

Figure 3 is a side view of one of the sections of which the loom is formed.

Figure 4 shows a section of an alternate design which is in the form of a clip angle as may be used in a corner of the loom.

Figure 5 shows one of the sections in the form of a curve and any radius or curve desired, or any combination of curves may be provided.

Figure 6 illustrates a section similar to that shown in Figure 3 showing holes instead of slots in the sections.

Figure 7 is a similar view showing teeth of an alternate design.

Figure 8 shows a needle in combination with a tube with which it may be used.

Figure 9 shows a cross section on line 9—9 of Figure 1 showing a telescoping strut or brace for supporting the loom.

Figure 10 is a cross section through the needle and tube.

Figure 11 is a detail showing a device for lifting and lowering the alternate strands of yarn or other material.

Figure 12 is a detail showing one of the units of the device shown in Figure 11.

In the drawing the loom is shown as it may be made wherein numeral 1 indicates a straight section of the loom, numeral 2, bolts for holding the sections together, and numeral 3, a needle.

The straight sections 1 may be of any suitable length, preferably from one to ten inches, and these are provided with pins or comb teeth 4, and openings in the form of slots 5, or holes 6 as shown in Figure 6, in which the section is indicated by the numeral 7 and the teeth by the numeral 8, or the teeth or openings may be of any design.

The pins may also be formed as shown in Figure 7, in which they are indicated by the numeral 9, and the section by the numeral 10.

The sections may also be curved as indicated by the numeral 11, in Figure 5, or formed at an angle as shown in Figure 4, as indicated by the numeral 12.

These sections may be assembled as shown in Figure 1, with curved and straight pieces laid out to conform to the contour of the pattern or shape of a sleeve, or any part of a garment or other object or device, and with the parts formed in this manner, the ends may overlap, or some parts may be formed with bent or flanged ends 13, as

shown on the sections 14 in Figure 1, or any means may be provided for separating or adding rigidity to the loom. The frame shown in Figure 1 is also provided with cross braces formed of sections 15, 16, and 17 in the upper part of the frame, and sections 18, 19, and 20 in the lower part, and the device may also be provided with a vertical strut or brace formed of parts 21, 22 and 23. These braces may be provided with slots 24 and openings 25, or either slots or openings may be used. The vertical strut is illustrated as telescoping with flanges 26 and 27 of the end members bent over the edges of the member 21, as shown in Figure 9. However, it will be understood that this strut may be formed similar to the lateral struts or struts of this type may be used in place of the lateral struts. The ends of the struts are flanged and secured to the side members of the frame as shown at the point 28, in which bolts 2, are placed through the flanges and sections of the frame. The loom illustrated in Figure 2 is similar to that shown in Figure 1, and this is also formed of strut sections 1, curved sections 11, and clips 12, and in this loom one portion is formed with small sections 29, 30 and 31, illustrating that straight sections may be used when it is desired to form curves, and these may be slightly bent if desired. This loom is also formed with inner braces 32, 33 and 34, which may be adjustable as illustrated.

As the loom may be relatively wide for some pieces of material, it may be desirable to provide a special needle, and in Figure 8, a needle 3, is illustrated in a small tubular member 35, which may be of the size of a soda straw or smaller, and may be slightly elongated as shown in Figure 10, so that this may be woven through the strands and then the needle slid through the tube and both the needle and tube withdrawn as a unit. It will be appreciated that a needle of any other type or design may be used.

It will be understood that although sections are illustrated as having teeth on one side, they may also be provided with teeth on both sides, as shown in Figure 6, and the teeth may be provided on all of the sections or on only part of the sections, as may be desired. It will also be understood that the sections 1, having teeth may also be used for the supports or braces, as will be noted in Figure 2, in which teeth are illustrated on one of the sections of the brace 33, and similar sections may be used in the design shown in Figure 1, or as desired.

The yarn or other material may be strung on the loom in the usual manner with the weft strands in one direction and then the warp strands woven through, and whereas these may be woven by the needle, it will also be understood that means may be provided for lifting the alternate strands to facilitate running the yarn

through. In Figures 11 and 12, a device is illustrated which is formed with upper and lower frames formed of sections 36 and 37, and 38 and 39, and the inner sections 37 and 38 are formed with offset portions or lips, 40 and 41, corresponding with every other strand. Yarn holding devices 42, are provided in the portions 40 and 41, and these are formed with upper lips 43, and lower lips 44, and a central eye 45, somewhat similar to the head of a safety-pin, and with a pin 46 held in one side, and formed so that it may be opened to remove yarn from the eye 45. These frames may be provided with knobs.

It will be understood that changes may be made in the construction without departing from the spirit of the invention. One of which changes may be in the use of sections or pieces of any other shape in cross sections, another may be in the use of other means for holding the sections together, and still another may be in the use of these parts in combination with a loom of any other type.

The construction will be readily understood from the foregoing description. In use the parts may be provided as shown and described and when it is desired to weave a garment or other object or device, a pattern or part thereof may be outlined and the parts of the loom assembled to correspond with the outline and joined together as shown. The braces may then be added to stiffen and support the frame.

The sections or parts may be made of various shapes, and although they are illustrated as being rigid it will be understood that all or some of the sections may be flexible or bendable, so that they may readily be bent or shaped to substantially any curve, shape, or design.

Having thus fully described the invention what I claim as new and desire to secure by Letters Patent is:

1. A loom for weaving sections of garments and the like to different patterns comprising substantially parallel side members, a base member, and an end member opposite the base member, characterized in that the said end member curves inward and away from the said base member, curving from the ends of the said side members, and then curves from each side toward the center forming an arc at the extreme end, and further characterized in that the said side, end, and base members are formed of relatively short, straight, curved, and angular shaped strips, with teeth projecting at the edges for holding threads in weaving, and means adjustably holding the strips together.

2. In a loom as described in claim 1 cross braces with the ends connected to said side, base, and end members.

CLARA C. GOLDEN.
